UNITED STATES PATENT OFFICE

2,008,686

FLOATING ROOF

Clayton L. Day, Chicago, Ill., assignor to Chicago Bridge & Iron Company, Chicago, Ill., a corporation of Illinois

Application January 10, 1931, Serial No. 507,977

3 Claims. (Cl. 220—26)

This invention relates to improvements in floating roofs and, more especially, such floating roofs as are commonly used on oil storage tanks to eliminate or lessen losses by evaporation, gas escape, and the like.

Among the features of my invention may be mentioned the following.

The roof has an annular pontoon giving it sufficient buoyancy so that it is non-sinkable.

10 The roof has an upstanding rim permitting the retention of water (for example, rain water) on top of the roof, such water acting as an insulator to keep the oil under the roof cool. As here shown, the upstanding rim is formed by the annular pontoon.

15 The roof is also provided with a depending annular rim forming a downwardly open gas-receiving space under the roof so that gas forming in the liquid or rising therefrom can be trapped in this gas-receiving space. As here shown, this depending rim is also formed by the annular pontoon.

20 The central portion of the floating roof may be flexible so that the same can flex upwardly some distance to increase the capacity of the gas-receiving space. This central portion, for example, may be made of flexible sheet metal.

25 The pontoon is high enough so that a substantial portion of it will be above the liquid on which the roof floats when substantially the entire area of the central sheet metal portion is in contact with said liquid. In a roof of this kind, it frequently is desirable to keep as much of the metal area of the roof in contact with the liquid as

30 possible. This contact will lessen evaporation from the surface of the liquid, and also lessen corrosion. My improved roof is so made that the entire central portion of the roof may be in contact with the liquid, and still a substantial portion of the pontoon will be above the liquid so that the roof will still have considerable buoyancy. In fact, it may be made and is here shown as having sufficient buoyancy in such case so that the central part may be entirely filled with water, and the roof still remain non-sinkable.

35 The roof is so made that as gas collects in the gas-receiving space, the flexible sheet metal central portion will flex upwardly to its maximum extent before the roof rises sufficiently to vent gas under the rim.

40 Another feature of the invention is the provision of an annular pontoon which is relatively deeper at the outside than the inside, in order to give greater buoyancy at the periphery. This additional buoyancy assists in supporting the

weight of the sealing means, for example, the shoes, hangers and other sealing means provided for sealing the space between the roof and the tank shell.

45 Other features and advantages of my invention will appear more fully as I proceed with my specification.

50 In that form of device embodying the features of my invention shown in the accompanying drawings—

55 Figure 1 is a vertical sectional view; Figs. 2, 3 and 4 are similar views showing the different ways of using the roof; and Fig. 5 is a similar view showing a modified form.

60 Another feature of my invention is the provision of means for causing some circulation of the oil. By using an annular pontoon, there is obtained some insulation of the oil near the periphery of the tank from heat above. This insulation is obtained by the confined air in the peripheral pontoon. Consequently, sun beating down on the roof will cause the oil in the center of the tank to heat more rapidly than under the periphery of the roof. This will cause some circulation of oil by convection in the tank, as indicated by the arrows in Fig. 3. That is, the oil under the pontoon will have a tendency to fall, move toward the center of the tank and there rise. This circulation will lessen or prevent undue heating of the oil directly under the central sheet metal portion of the roof and thus lessen losses.

65 As shown in the drawings, 10 may indicate a cylindrical tank in which is stored oil or other liquid 11.

70 Any means, such as the shoes 14, hangers 14^a and flexible fabric seal 15, may be employed for sealing the space between the periphery of the roof and the wall of the tank 10. Such sealing means, however, forms no part of the present invention and, consequently, the same need not be described in detail here. The roof may also be provided with a manhole 16 giving access to the interior of the pontoon and a manhole 17 in the central portion of the roof. Numeral 18 may indicate a gage hatch. The central part 75 of the roof may be provided with a sump 19 having a cover 20, and a drainage system of any desired construction, as indicated by 21 may lead from the sump to the outside of the tank.

80 The roof itself comprises primarily a peripheral circular pontoon 12 and a central sheet metal portion 13. The interior of the pontoon may be braced by suitable truss members 22.

85 The pontoon is preferably so made as to pro-

vide an upstanding rim 23 surrounding the roof permitting the retention of rain water thereon. It is also here shown as formed to provide a depending rim 24 to form a downwardly open 5 gas-receiving space under the roof. As here shown, the rim 24 constitutes the bottom of the pontoon, the rim being formed by slanting this bottom downwardly and outwardly from the edge where it is attached to the periphery of the 10 central portion 13. By this construction, it will be seen that a radial cross-section of the pontoon is substantially rectangular but somewhat deeper at the outer edge than the inner edge. The bottom of the surface of the pontoon, therefore, forms the downwardly projecting rim above 15 referred to.

The central part of the roof may be provided with a vent pipe 25 controlled by a valve 26. When the roof is first put into use, or at other 20 times, if desired, this vent pipe may be used to permit the escape of air or other gases from under the roof. After the roof has been put into use and air permitted to escape from underneath, the valve 26 may then be closed so that 25 gas arising from the liquid by boiling or otherwise will be trapped and retained under the roof. In Fig. 2 the roof is shown in use in this manner. It will be seen that there is a gas space 27 under the roof. Since the central portion 13 30 of the deck is made flexible, it may flex upwardly and downwardly to vary the capacity of this gas space. For example, as shown in Fig. 2, the central portion 13 is flexed upwardly to a considerable extent, giving a relatively large gas 35 space under the roof. The roof is preferably designed so that this upward flexing will be carried to its maximum point before any gas will escape under the rim of the roof. As gas in the space 27 condenses, or goes back into the liquid, or decreases in volume, the central portion 13 of the roof will flex downwardly to decrease the volume of the gas space. This upwardly and downwardly flexing of the central portion of the roof 13 to change the capacity of 45 the gas space under the same, in accordance with changes in pressure of the gas, is sometimes referred to as "breathing". That is, the flexible central portion 13 will permit a "breathing" action of the roof. It is to be particularly noted, 50 however, that the breathing action is not due solely to the flexible central portion of the roof. That is, even if the central portion 13 were not flexible but made rigid, the roof would breathe somewhat by rising and falling bodily. Reference to Fig. 2 will show that the gas space 27 is 55 not formed entirely by the upward flexing of the central portion 13 but that the whole roof has risen bodily somewhat and that this upward bodily movement has formed a part of the gas space 27. That is, the roof also "breathes" by its bodily upward and downward movement. For example, as diagrammatically shown in Fig. 5, the central portion 13 may be stiffened and prevented from flexing by radially arranged trussing 60 65 70 75 75 and there may still be formed a gas space 27, as shown by the bodily rising of the roof. Also, the capacity of this gas space will vary with changes in pressure of the gas. That is, the roof will rise or fall in accordance with different pressures and quantities of gas formed under the same to vary the capacity of the space 27. Such a roof, therefore, even though it does not have a flexible central portion 13, will still have a breathing action. Making the central portion flexible will increase the maximum capacity of

the space 27. By making the central portion flexible, therefore, the maximum capacity of the space 27 can be increased without lowering the depending peripheral rim. Increasing the vapor capacity in this manner does not interfere with the stability of the roof or its minimum capacity. That is, the vapor space 27 can be increased in capacity by lowering the rim or by making the central portion flexible. Lowering the rim, however, might interfere with the stability of the roof and will also interfere with its minimum capacity because a lower rim will strike the bottom of the tank sooner than a higher one. Some increase to the maximum capacity of the space 27 may, therefore, be provided by making the central portion 13 flexible without interfering with the stability of the roof or its minimum capacity.

If desired, all the gas under the roof may be permitted to escape through the vent pipe 25 so that the entire area of the central portion 13 of the roof will be in contact with the surface of the oil. The roof in use in this manner is shown in Fig. 3. This contact of the central metal portion 13 will serve to lessen or stop evaporation from the surface of the oil. Of course, some gas may collect by boiling but if this occurs, any such gas collected may be vented off through the vent pipe. Ordinarily, when the roof is exposed to the sun's rays, boiling will occur first at the top since the upper surface of the oil will become heated by contact with the metal of the roof. As explained before, however, the pontoon will provide some insulation at the periphery so that the oil near the wall of the tank will be cooler than in the center and this will cause circulation, as shown by the arrows, which will serve to lessen or prevent boiling of the oil at the surface, as just referred to. In short, it may be stated that the roof may be used, as shown in Fig. 3, with the central portion 13 having its entire area in contact with the surface of the oil. It may be maintained in this position by immediately venting any gas through the pipe 25 as soon as it collects under 40 the roof. If desired, of course, the valve 26 can be left open all of the time so that no gas can collect. The roof will then operate as shown in Fig. 3.

The upstanding rim 23 surrounding the central portion 13 permits the retention of water, such as rain water 29, on top of the roof, such layer of rain water serving to insulate the oil against heat. In Fig. 4, the roof is shown as being used with a layer of rain water on top of it for such insulating purposes. In such case, the valve 26 may be left open so that no gas can collect under the roof or it may be kept closed and some gas permitted to collect. In case more gas than desired collects, the valve may be opened and a sufficient amount vented.

While I have shown and described certain embodiments of my invention, it is to be understood that it is capable of many modifications. Changes, therefore, in the construction and arrangement may be made without departing from the spirit and scope of the invention as disclosed in the appended claims, in which it is my intention to claim all novelty inherent in my invention as broadly as permissible, in view of the prior art.

What I regard as new, and desire to secure by Letters Patent, is:

1. A floating roof, including; a substantially flat sheet supported by an annular pontoon, a portion of said pontoon forming an upstanding rim around

the flat sheet; and a downwardly depending continuous rim surrounding said sheet.

2. A floating roof, including, a substantially flat sheet supported by an annular pontoon, a portion 5 of said pontoon forming an upstanding rim around the flat sheet, and a portion of said pontoon forming a depending rim around the flat sheet to form a gas spaced under the flat sheet and inside of said depending rim.

3. A floating roof, including, a substantially flat sheet supported by an annular pontoon having inner and outer and top and bottom walls, said sheet being attached to the lower edge of said inner wall, and said bottom wall slanted downwardly and outwardly to form a gas space under said sheet. 5
